DOWEL MACHINE

Marcel Despres, Grand Rapids, Mich.

Application July 29, 1941, Serial No. 404,489

8 Claims. (Cl. 144—30)

This invention relates to machines for producing dowels. Dowels are short lengths cut from rods of uniform cross-section and generally each end of the dowel has a continuous beveled annular surface. The dowels are used particularly in furniture construction and in other places where wood members are to be secured together, end portions of the dowels being inserted and glued in holes in the members which are to be connected.

My invention is directed primarily to a machine for producing dowels very rapidly and in large quantities from elongated rods of the proper diameter. Dowels heretofore in practice have generally been cut one at a time, the rod being fed in periodic movements a distance equal to the length of one dowel which is severed from an end portion of the rod, there being a succeeding lengthwise movement of the rod of the dowel length distance and a severing, and these steps repeated until the rod is consumed.

With my invention the rod is fed in periodic movements but a far greater length equal to a multiple of the length of a single dowel. When thus fed this longer distance into the machine it is held in proper position and cut transversely to the length of the dowel, and the ends of the dowel are also beveled at one time. The severed dowels drop through the machine and out of the way after which there is an immediate succeeding feeding of the rod from which the dowels are made the same distance into the machine with a repetition of the cutting of a large number of dowels simultaneously. This greatly increases the number of dowels which can be produced in a given time.

My invention is directed to novel construction for effectively producing dowels in large quantity production as described, and is concerned with novel means for feeding the rod and controlling the feed, for rotating the rod while it is being acted upon by the severing and beveling saws and cutters, for moving the saws out of the way when not used, and to operative position when they are to cut and finish the plurality of dowels and, in general, for effectively attaining very large production of dowels.

An understanding of the invention may be had from the following description taken in connection with the accompanying drawings, in which,

Fig. 1 is an elevation of a machine made in accordance with my invention.

Fig. 2 is an end elevation of the upper portion of the machine.

Fig. 3 is an opposite end elevation thereof.

Fig. 4 is a plan view.

Fig. 5 is a transverse vertical section through the machine between its ends.

Figs. 6 and 7 are fragmentary transverse vertical sections through the upper part of the machine at different planes to better illustrate the construction.

Fig. 8 is an elevation in detail of the feeding mechanism.

Fig. 9 is a fragmentary elevation illustrative of the means used to rotate the rod from which the dowels are cut, and

Fig. 10 is a view showing a finished dowel and indicating the process which is followed in producing the dowels with beveled ends.

Like reference characters refer to like parts in the several figures of the drawings.

The dowels are cut from an elongated rod 1 which is circular in cross-section and of small diameter. The dowels 2 (Fig. 10) are of short lengths and at each end are beveled as indicated at 3. The dowels are cut from the rod by a transverse cut and at the cut a V-shaped groove around the rod is made so as to simultaneously bevel the adjacent ends of two dowels.

In the machine which I have devised for producing the dowels 2 from an elongated rod 1 of the proper diameter, two vertical end frames 4 are connected together and spaced from each other by horizontal cross bars 5. The upper ends of the frames 4 are reduced in width and extended upwardly as at 6. Between and over the upper ends of the parts 6 a horizontal bar 7 is placed and secured to provide a firm frame structure.

The dowel is fed lengthwise into the machine over a horizontal bar 8 extending between the ends and in the upper portion of the machine so that the free end of the rod may not bend downwardly to a position where it cannot be operated upon. The rod when it has been moved to a determined position in the machine is acted upon by a plurality of circular saws 9 and grooving cutters 10 mounted respectively upon horizontal shafts 11 and 12 located at opposite sides of the upper portion of the machine, the saws and cutters being spaced the right distance by sleeves 13 around the shafts.

The shafts 11 and 12 are carried at the upper ends of the generally vertical arms 14 of bell crank levers, one adjacent each end of the machine for each shaft which are mounted upon elongated rods 15, one at each side of the machine and carried at their ends by the frames 4. Said bell crank levers have outwardly extending

substantially horizontal arms 16, which at each side of the machine are connected by a bar 17 to make a unit. The arms 16 pass above shafts 18, one at each side of the machine and extending between the upper corners thereof, and mounted for rotation, resting upon cams 19 on said shafts. With the rotation of the shafts the raises in the cams 19 coming underneath the arms 16 turn the bell crank levers to swing the saws 9 and grooving cutters 10 inwardly to engage with the rod 1. The saws and cutters will be moved substantially simultaneously toward each other and, as will be later described, the rod being rotated about its horizontal axis, grooves are cut so as to provide the beveled ends 3 and the saws passing at least to and slightly across the axis of the rod sever the dowels therefrom producing as many dowels as there are saws at each operation. In practice it is desirable that the grooving take place slightly ahead of the sawing of the rod into dowels.

An electric motor 20 is mounted at a lower part of the frame on the shaft on which are two drive pulleys 21. The shafts 12 at one end are provided with pulleys 22. Endless belts 23 pass around the pulleys 22 and the drive pulleys 21 whereby the shafts 12 with the saws and grooving cutters thereon are continuously operated at high speed.

A horizontal drive shaft 24 is mounted in suitable bearings on the ends of the frame and extends therethrough, being equipped with a pulley 25 at one end which through a suitable belt drive may be driven from any source of power. The opposite end of the shaft 24 carries a sprocket wheel 26 located at the same end and above the pulleys 21 previously described. The shafts 18 at the same end of the frame are equipped each with a sprocket wheel 27. A single endless chain 28 passes around all of the sprockets 26 and 27 and underneath a chain tensioning idle sprocket 27a which is suitably mounted on the adjacent end 4 of the frame whereby the shafts 18 are driven simultaneously and in equal amounts.

The dowel rod 1 is guided through the upwardly extending end 6 of the end of the frame opposite that at which the belt drive 23 and chain drive 28 are located, passing through a guide 29 (Fig. 4) and over the bar 8. Upon such bar 8 near the guide 29 an arm 30 is secured or is cast integral therewith. The arm 30 is horizontal (Fig. 7) and above and on it an idle grooved feeding roller 31 is mounted located at one side of the dowel rod 1. At the opposite side a driven feed roller 32 of the same form is positioned though inclined to the horizontal (Fig. 7). It is secured at the upper end of a shaft which passes in a downward direction through a sleeve 33 which has a downwardly extending arm 34 (Fig. 8) mounted for rocking movement on a short horizontal shaft 35 and mounted in a bearing on the adjacent end 4 of the frame. At its outer end the shaft 35 is equipped with a spur pinion 37. A beveled pinion 36 is pinned to the inner end of shaft 35 and is in mesh with a beveled pinion 38 at the lower end of the shaft which carries the roller 32. One of the shafts 18 is equipped with a gear 39 which is in mesh with the pinion 37. The feed roller 32 is therefore continuously driven but at a higher speed than the shaft 18 because of the difference in sizes of the gear 39 and pinion 37.

An arm 40 (Fig. 7) integral or permanently

connected with the sleeve 33 extends outwardly over a shaft 18 and bears upon a cam 41. When the rise in said cam comes underneath the arm the continuously driven roller 32 comes against the rod 1 and presses it against the idle pulley 31 whereupon the rod is moved lengthwise into the machine until the rise in the cam 41 passes and the feed roller 32 is permitted to fall away from the rod. It is evident from this structure that with each rotation of the shaft 18 there is a feeding of the rod into the machine with an interval between successive feedings. It is during said interval that the cutting saws and grooving cutters are brought into operative cutting and grooving relation with the rod which has been fed into the machine and the dowels cut therefrom.

At each side and at each end of the machine an elongated vertically positioned member 42 is located said members having pivotal mounts at their lower ends at 43 on the adjacent ends 4 of the frame. Each of said members is widened at its upper end and each at an upper corner has a laterally extending lug 44 (Fig. 5) which bears against a cam 45 on each shaft 18. The members 42 at their upper ends at each end of the machine are tended to be forced apart by a compression spring 46 located between them (Fig. 4). Each at its upper portion and adjacent its inner edge is provided with an elongated vertical slot 47. It is evident that the members swing back and forth upon their pivots 43 under the action of the cams 45 and springs 46 during the operation of the machine.

Two bars 48 are disposed lengthwise of the machine, one of said bars between the two members 42 at each side of the machine. Said bars are equipped with rollers 49 at their ends which are received within the slots 47. At each end of each bar a link 50 is pivotally connected, said links extending downward and at their lower ends formed with eccentric housings to cooperate with eccentrics 51 secured on the shaft 24. There are four eccentrics as shown in Fig. 1. With each complete rotation of the shaft 24 each bar 48 traverses its slots 47 upwardly and downwardly making a complete reciprocation. As shown in Fig. 5, the bars traverse said slots simultaneously and in opposite directions.

A plurality of dowel rod engaging members 52 are associated with each of the bars 48 extending in a vertical direction and pivotally mounted at their lower ends between ears 53 on the bars 48 through which a pivot rod 54 passes, it being understood that a pair of such members 52 is provided for each dowel that is cut during a machine cycle of operations. The members 52 are held in vertical position against sidewise movement, passing through slots in plates 55, one on each of the bars 48, which plates extend horizontally outward therefrom (Figs. 5 and 9). A spring 56 between each member 52 and its bar 48 holds the members in vertical position against the bars. Each of the members 52 at its inner edge is serrated with teeth, the teeth on one set or series of members at one side of the dowel rod being directed downward and the others upward as shown in Fig. 5.

With this construction after the prescribed length of the dowel rod has been fed into the machine the rises on the cams 45 come to the lugs 44, moving the members 42 inward toward each other and, therefore, carrying the dowel rod engaging members 52 inwardly toward each other to come against opposite sides of the rod

1. Reciprocation in opposite direction of the bars 48 and the members 52 carried thereby, together with the opposite positioning of the serrations or teeth on said members 52 results in a continuous rotation of the rod 1. At the same time the cut-off saws 9 and the grooving cutters 10 are brought inwardly toward each other to engage with the dowel rod whereby the operation of severing the dowels and beveling the ends occur simultaneously with a continuous turning movement of the rod about its longitudinal axis. When the rises on the cams 45 leave the lugs 44 the springs 46 move the members 42 and the parts carried thereby away from each other. It is while the parts are thus separated that the feeding of the rod by the grooved feeding pulleys 31 and 32 takes place.

The dowel rod when fed into the machine will lie against the upper side of the bar 8, and it is very desirable that the rod be lifted a short distance above such bar during the time that the dowel cutting operation occurs. For this purpose lifters are provided. At one side of the machine stationary lifting members 57 are provided and at the other side of the machine movable lifting members 57a are pivotally suspended at their upper ends from a rod 58 extending between the narrow upper portion 6 of the machine underneath the bar 7. Said members 57 and 57a include each a plurality of arms spaced from each other extending downwardly between the saws and grooving cutters. The end arms 57b of the members 57a are extended farther downward and are offset (Fig. 6) and by the force of coiled tension springs 59 bear at their ends against cams 60, mounted upon the shafts 18, whereby with each rotation of said shafts the movable arms 57b are moved toward the stationary arms by said cams and away therefrom by said springs after the rises on the cams have passed. The configuration of the cams is such that the arms are opened suddenly and immediately start to close.

On the arms inwardly extending lugs 61 having V-shaped notches therein extend toward each other and are located in a position that when the movable arms move toward the stationary arms said lugs engage the dowel rod and hold it at opposite sides in the notches (Fig. 5) lifting the rod above the bar 8 and holding it in a horizontal position and without parts of the rod being lower than the other parts thereof, thereby insuring that the cutting of the dowels shall be square across and substantially perfect.

In the upper extension 6 of the frame 4 opposite the guide 29 an adjustable screw 62 is mounted (Fig. 4) which serves as a stop against which the end of the dowel rod comes when it is fed into the machine, insuring that the extent of the rod fed into the machine shall be accurate and uniform and, therefore, the dowels cut shall be uniform throughout the entire operation of the machine.

With this machine as described, the rod 1 passing through the guide at 29 is fed into the machine by the grooved feeding rollers 31 and 32 until the rod strikes the stop at 62. Substantially simultaneous with the engagement with the stop the feeding is rendered ineffective by the cam 41 (Fig. 7) dropping away from the arm 40. Thereafter and immediately following, the dowel rod turning members 52 are brought against opposite sides of the rod by the operation of the cams 45 against the lugs 44, and the rod lifting members 61 are brought into engage-

ment with opposite sides of the rod. Immediately thereafter the grooving cutters 10 and the cut-off saws 9 are moved inwardly toward the rod, grooving the rod and cutting the dowels off at such grooves. When this operation is finished the saws and grooving cutters, the rod rotating members 52 and the rod lifting devices 57a, 61 move outwardly to inoperative position opening the machine for the next succeeding feeding movement of the rod 1 until it again strikes the stop at 62. The operation may be repeated indefinitely until the length of the rod 1 is used up and continued to be repeated with succeeding rods. The machine operates continuously and goes through the performance described whether or not a dowel rod is fed into the machine. It is only necessary to insert the rod into the machine a distance such that it will be engaged by the feeding rollers 31 and 32.

It is evident from the foregoing that a machine capable of very great quantity production of dowels is provided. The construction is practical and efficient.

The invention is defined in the claims and is to be considered comprehensive of all forms of structure coming within their scope.

I claim:

1. In a machine for cutting dowels, means for feeding a predetermined length of rod equal to the combined length of a plurality of dowels, means for stopping the rod at a predetermined position, vertical bars at each side of the rod, means for reciprocating said bars in opposite directions, means for alternately moving said bars toward the rod to engage therewith and away from the rod to disengage therefrom, said engagement occurring at the times between longitudinal feeding movements of said rod, said bars at their engaging edges having serrations thereon oppositely positioned, whereby the rod is continuously rotated when engaged by said bars, a shaft mounted to one side of the rod having a plurality of circular saws thereon spaced from each other in accordance with the lengths of dowels to be cut, means for continuously driving said shaft, and means for alternately moving the shaft and saws thereon toward the dowel rod and away therefrom, said movements toward the dowel rod taking place simultaneously with rotation thereof.

2. A construction containing the elements in combination defined in claim 1 combined with a second shaft mounted for rotation at the opposite side of the dowel rod, a plurality of grooving disks mounted on said second shaft and spaced to lie in the same vertical planes with the cutting saws, and means for moving said shaft and grooving disks thereon toward and away from the dowel rod, said movement toward the dowel rod occurring during its longitudinal rotation.

3. In a dowel cutting machine, a horizontal guide through which a dowel rod may be inserted, a fixed grooved roller mounted to turn about a vertical axis located to one side of the guide, a second grooved roller mounted at the opposite side of the guide between which rollers the dowel rod is adapted to be inserted, a shaft on which the second roller is fixed, a pivotally mounted journal bracket carrying the shaft, means for continuously driving the shaft, a second continuously driven shaft, a cam on said shaft having a rise and an arm extending from said journal bracket to and riding against said cam, whereby the second roller may be brought against the dowel rod and pressed against the first grooved roller during

the time that the rise on the cam is engaged with said arm.

4. In a dowel cutting machine, means for feeding a predetermined length of a dowel rod into the machine, a stop against which an end of the rod engages, continuously operating means for cutting the infed length of the dowel rod transversely to simultaneously cut a plurality of dowels therefrom, two pairs of vertically positioned members, one at each end of the machine, each member having an eccentric housing at its lower end, a driven shaft, eccentrics thereon within the housings of said members for reciprocating one member of each of said pairs of members upwardly simultaneously with a downward reciprocating movement of the other members and vice versa, two horizontal bars extending one between the upper ends of and connected to the members at each side of the machine, two series of upwardly extending driving bars pivotally connected to said horizontal bars at their lower ends, those connected to one bar being to one side of the dowel rod and those to the other at the opposite side, one of said series of bars at their inner edges having serrations extending downwardly and inwardly and the other upwardly and inwardly, and means for periodically moving said members, bars and driving bars associated therewith toward each other to engage the driving bars with said dowel rod and rotate about its longitudinal axis.

5. A construction containing the elements in combination defined in claim 4, said last mentioned means comprising, vertically positioned members pivotally mounted at their lower ends and each having a vertical slot therein, rollers at the ends of said horizontal bars positioned in said slots, continuously driven shafts and cams on the shafts to engage with the upper end portions of said pivotally mounted members at periods of the rotation of said shafts to move said upper end portions toward each other.

6. In a dowel cutting machine, continuously operable feeding means for feeding a predetermined length of a dowel rod into the machine, a stop against which an end of the rod engages, means for periodically rendering said feeding means operative and inoperative, means for rotating the rod about its longitudinal axis during the times that the feeding means is inoperative, two shafts located one at each side of the dowel rod and parallel thereto, a plurality of spaced cutting saws mounted on one shaft, a plurality of

spaced grooving cutters mounted on the other shaft, bell crank levers having upwardly extending arms on which said shafts are mounted, means for driving said saw and cutter shafts, two additional driven shafts, and cams thereon, said bell crank levers having outwardly extending arms resting upon said cams, whereby the cutting saws and grooving cutters are periodically moved inwardly toward each other to act upon the rod, as specified.

7. In a dowel cutting machine, means for periodically feeding a predetermined length of a dowel rod into the machine, a horizontal bar over which the rod is fed, two members, one pivotally suspended at its upper ends above said rod and bar and extending downwardly one to each side of the rod and bar, said members having a plurality of notched projections extending toward the bar, a driven shaft, a cam thereon bearing against said pivotally suspended member at its lower ends whereby at predetermined times in the rotation of said shaft, said notched projections are brought against the dowel rod to engage and hold it in horizontal position above said bar, and yielding means normally forcing said suspended member at its lower portions against the cams.

8. In a dowel cutting machine, means for periodically feeding a dowel rod into the machine a predetermined distance equal to the combined lengths of a plurality of dowels to be cut, continuously operated means for rotating the rod, means to bring said rotating means into operative engagement with the rod at the times between periodic longitudinal feeding movement thereof, a plurality of continuously driven saws spaced apart from each other distances equal to the lengths of dowels to be cut and mounted to rotate on an axis parallel to the length of the rod, means for alternately moving said saws toward and away from the rod, said movements toward the rod to engage therewith and cut dowels occurring at the times between the periodic longitudinal feeding movements of the rod, a plurality of rotatably mounted grooving disks located in substantially the same planes with companion cutting saws, means for continuously driving said disks and means for periodically moving the same toward and away from the rod occurring in synchronism with the movements of said cutting saws.

MARCEL DESPRES.
